US00D760717S

(12) **United States Design Patent**
Solomon et al.

(10) **Patent No.:** **US D760,717 S**
(45) **Date of Patent:** **** Jul. 5, 2016**

(54) **WATCH BODY**

(71) Applicant: **Pebble Technology, Corp.**, Redwood City, CA (US)

(72) Inventors: **Mark Charles Solomon**, San Jose, CA (US); **Christopher Paul Ioffreda**, San Francisco, CA (US); **Andrew James Witte**, Palo Alto, CA (US); **Steven William Johns**, Vancouver (CA); **Sean E. Daley**, San Jose, CA (US); **Nicholas Harold Ford**, Kitchener (CA); **Troy Garrett Tye**, San Jose, CA (US)

(73) Assignee: **Pebble Technology, Corp.**, Palo Alto, CA (US)

(**) Term: **15 Years**

(21) Appl. No.: **29/548,667**

(22) Filed: **Dec. 15, 2015**

Related U.S. Application Data

(63) Continuation of application No. 29/533,825, filed on Jul. 22, 2015.

U.S. Appl. No. 29/533,825, filed Jul. 22, 2015, Solomon.

Primary Examiner — Barbara Fox

(74) *Attorney, Agent, or Firm* — Rutan & Tucker, LLP

(57) **CLAIM**

The ornamental design for a watch body, as shown and described.

DESCRIPTION

FIG. 1 is a perspective view showing a front of a watch body according to our new design;

FIG. 2 is a perspective view showing a back of the watch body;

FIG. 3 is a plan view of the front of the watch body;

FIG. 4 is a plan view of a back of the watch body;

FIG. 5 is an elevational view of a right side of the watch body;

FIG. 6 is an elevational view of a left side of the watch body;

FIG. 7 is an end view of a top end of the watch body; and,

FIG. 8 is an end view of a bottom end of the watch body.

The broken lines shown in the drawings represent portions of the watch body that form no part of the claimed design.

1 Claim, 3 Drawing Sheets
